J. D. CALLAHAN.
TRAIN PIPE HANGER.
APPLICATION FILED DEC. 11, 1913.

1,099,018.

Patented June 2, 1914.

UNITED STATES PATENT OFFICE.

JACOB D. CALLAHAN, OF JERSEY SHORE, PENNSYLVANIA.

TRAIN-PIPE HANGER.

1,099,018.

Specification of Letters Patent. Patented June 2, 1914.

Application filed December 11, 1913. Serial No. 806,056.

To all whom it may concern:

Be it known that I, JACOB D. CALLAHAN, a citizen of the United States, residing at Jersey Shore, in the county of Lycoming and State of Pennsylvania, have invented certain new and useful Improvements in Train-Pipe Hangers; and I do hereby declare the following to be a full, clear, and exact description of the invention, such as will enable others skilled in the art to which it app pertains to make and use the same, reference being had to the accompanying drawings, and to the letters and figures of reference marked thereon, which form a part of this specification.

This invention relates to new and useful improvements in devices for supporting train pipes and comprises a simple and efficient device of this nature, consisting of a hanger made up of two parts, one of which is adapted to be fastened to the frame of a car and the sections having interlocking connections.

The invention comprises various details of construction and combinations and arrangements of parts which will be hereinafter fully described, shown in the accompanying drawings and then specifically defined in the appended claim.

I illustrate my invention in the accompanying drawings, in which:—

Figure 1 is a side elevation of the hanger made in accordance with my invention. Fig. 2 is a sectional view through the interlocked ends of the hanger sections. Fig. 3 is an end view, and Fig. 4 is a detail perspective view of one end of one of the hanger sections.

Reference now being had to the details of the drawings by letter, A designates a hanger section, one end A' of which is adapted to be fastened to the under surface of a car in any suitable manner and a laterally projecting portion B of the hanger has a bearing C for the pipe and has an upwardly extending end portion D which is apertured as at D', the upper marginal edge E of the aperture being convexed.

F designates a part of the pipe supporting

and holding device, having a concaved bearing recess F' coöperating with the concaved bearing surface C to surround and frictionally engage the pipe and has a tongue H concaved as at H' adapted to conform to the convexed surface E formed at the end 55 wall of the aperture D' which is engaged thereby when the parts are adjusted together in the manner shown in Fig. 1 of the drawings.

The hanger sections A and F have registering apertures K formed in the integral bosses N and the boss in the section F is recessed away as at Q to receive the head R of the bolt R' which passes through said registering apertures and is adapted to be engaged by a nut T on the threaded end of the bolt, thus forming means coöperating with the interlocking ends for holding the two sections together.

What I claim to be new is:—

A hanger for supporting train pipes comprising a bracket arm adapted to be attached to the under surface of a car and having a laterally extending arm terminating at one end in a cylindrical crosspiece with a slot 75 leading through said laterally projecting portion adjacent to the crosspiece, said bracket arm having a recess upon its upper edge adjacent to its free end and a vertically disposed aperture, a plate having an aperture registering with the aperture in said bracket arm and provided with a recess about the aperture, a bolt passing through said registering apertures and having a head seated in said recess, the under edge of said plate having a groove in registration with the recess in the upper edge of said bracket arm, and a contracted curved finger extending through the slot in the bracket arm and having a concaved surface engaging the convexed surface of said crosspiece, as set forth.

In testimony whereof I hereunto affix my signature in presence of two witnesses.

JACOB D. CALLAHAN.

Witnesses:

G. M. CALBECH,
Geo. HETFIELD.
